RIBBON SPOOL

Rawson Atwood, Brooklyn, N. Y., assignor to
Decorated Metal Manufacturing Company,
Brooklyn, N. Y., a corporation of New York

Application August 22, 1935, Serial No. 37,295

2 Claims. (Cl. 242—74)

This invention relates to improvements in spools for ribbons and the like and particularly but not limited to spools for ink ribbons used in typewriters, business machines, etc.

According to common practice in the use of such spools in such machines, the spools themselves are supplied by the manufacturer thereof to ink ribbon manufacturers, who in turn wind the ink ribbon thereon and supply the unit (spool and ink ribbon) to the users of the machines.

Such spools must be sold at a very low price as, according to the usual practice, the spools are thrown away after one use thereof. For this reason they must be produced at a very low cost of manufacture. Furthermore, re-use of such spools is very undesirable from the point of view of the ink ribbon manufacturer because such re-use may result in the winding thereon and use therewith of other ribbons inferior in quality to those supplied by him with such spools.

It is the object of the present invention to provide a spool which will meet these conditions.

In the accompanying drawing,

Figure 1 is a cross-section of a spool embodying the present invention showing the same open for the reception of the end of the ribbon to be wound thereon;

Figure 2 is a similar section showing the same closed with the end of the ribbon secured to the spool; and

Figure 3 is a perspective view of the spool with the ribbon wound thereon.

Referring to said drawing, the spool *a*, which is of resilient sheet metal, is slit longitudinally and is bent at one edge to provide an inwardly projecting tubular portion *b* and at its other edge to provide a socket *c* for the reception of and corresponding transversely in shape to the projection *b*. These two members *b*, *c*, constitute the means for locking the spool in closed position and in doing so clamping the end of the ribbon to be

wound upon the spool and holding it in that position during the unwinding and use of the ribbon, the fact being that, when the projection *b* is forced into the socket *c* from the position in which it is shown in Figure 1 to that shown in Figure 2, the projection *b* will be forced into the socket *c* and interlocked therewith and the ribbon end clamped therein, as shown in Figures 2 and 3. For the purpose of such interlocking and clamping, the diameter of the projection *b* is slightly larger than the distance between the upper ends of the socket so that when the projection is forced into the socket, it and the ends of the socket will yield in passing each other because of their resiliency and then snap into engagement at a point above the centre of the projection and thereby lock it frictionally against accidental or unintended separation from the socket. The fit of the two will not only effect such interlocking but, in doing so, clamp the ribbon end tightly between them.

What I claim is:

1. A ribbon spool of resilient sheet metal having a longitudinal slit for receiving the ribbon end and at opposite edges of said slit having coacting means adapted on the application of pressure of one towards and into engagement with the other to interlock and clamp the ribbon end to the cylinder, said interlocking means comprising a projection on one edge and a socket on the other for receiving it.

2. A ribbon spool of resilient material having a longitudinal slit for receiving the ribbon end and at opposite edges of said slit having coacting means adapted on the application of pressure of one towards and into engagement with the other to interlock and clamp the ribbon end to the cylinder, said interlocking means comprising a projection on one edge and a socket on the other for receiving it.

RAWSON ATWOOD.
